UNITED STATES PATENT OFFICE.

ALICE M. WRIGHT, OF DETROIT, MICHIGAN.

ELECTRIC OVEN FOR HAIR.

Application filed September 28, 1922. Serial No. 591,051.

To all whom it may concern:

Be it known that I, ALICE M. WRIGHT, a citizen of the United States of America, residing at Detroit, in the county of Wayne 5 and State of Michigan, have invented certain new and useful Improvements in Electric Ovens for Hair, of which the following is a specification, reference being had therein to the accompanying drawings.

10 This invention relates to an oven adapted to be used in imparting what is known as a permanent wave or curl in hair.

It has for its primary object to provide a heater adapted for use upon hair upon 15 the head of the operator.

Another object of the invention is to provide a heater capable of being readily modified for use in various locations with curls or waves of various forms and with locks or 20 tufts of hair of different sizes.

A further object of the invention is to provide a heater in which hair wound upon any suitable form of hair curler may be subjected to moisture and heat, but in which 25 steam produced may readily escape.

Further objects of the invention will appear in the specification, the drawing illustrating a preferred embodiment of the invention, together with certain desirable 30 modifications and attachments.

Figure 1 is a perspective view of the device as it appears while in use;

Fig. 2 is a perspective view, parts being broken away of one of the sections with the 35 removable heating plate detached;

Fig. 3 is a perspective view of a preferred form of heating plate shown in position in Fig. 1;

Fig. 4 is a side elevation of a modified 40 form of plate;

Fig. 5 is a perspective view illustrating a preferred form of cloth and curler for use with the oven;

Fig. 6 is a transverse sectional view 45 through one of the hollow casings or shells to which the heating plates are attached;

Fig. 7 is a plan view of an attachment shown as secured to one of the oven sections;

50 Fig. 8 is a side elevation showing two of the attachments illustrated in plan in Fig. 7, secured in position upon the heater, and

Fig. 9 is a section of a modified heating member.

55 The heater comprises a pair of hollow shells 1, 2, preferably made of aluminum or

of one of its alloys. Secured to each of these shells 1 and 2 or preferably formed integral therewith are handle members 3 and 4 to which may be secured handles 5 and 6 60 of wood or other heat insulating material.

As illustrated most clearly in Figs. 2 and 6, the shell 2 is provided with a lining 7 of asbestos or other heat insulating material and the top of the shell is preferably provided with a cover plate 8 of thin metal secured within the shell in any suitable manner. Within the box-like structure formed by the lining 7 and the cover plate 8 is mounted an electric heating element 9 70 of any suitable construction having outside terminal posts 10, 11, which may be connected by wires 12 with any suitable source of electricity. Upon the confronting faces of these heating sections are secured plates 75 13, these plates being held in position by any suitable means as by spring clips 14 engaging within suitable depressions 15 in the ends of the plates.

In Fig. 5 a curling pin 16 is shown in 80 which a central wire 17 lies between two outer parallel wires upon which the hair may be wound and held by the engagement of the end of the wire 17 with a loop portion 18 of the curler. The wire 17 extends through an open ended pocket 85 formed at one end of a cloth 19. After the hair is wound upon the curler, the moistened cloth 19 is secured to the wire 17 which is then placed within the loop 18. 90 The cloth is then wrapped around the hair twisted upon the curler. The roll formed by the hair and cloth is then grasped between the heating plates 13, the temperature 95 of which is sufficient to raise the water in the cloth 19 almost to the boiling point. Any steam that may be formed can escape at the sides or ends of the oven constituted by the space between the heating plates, 100 and by proper regulation of the temperature no injury will be done to the hair. The handle members 3 and 4 are normally forced apart by a spring 20 so that when the device is applied to the hair the plates 13 105 are separated to receive the hair with its wrapping and the operator may apply as much pressure as is desired by pressing together upon the handles 5 and 6.

While the plates 13 are preferably provided with a concave face as shown in Fig. 3, it will be evident that plates having different configurations may readily be sub- 110

stituted therefor. In Fig. 4, plates 21 are shown having corrugated interfitting faces suitable for use upon a strand of hair which has not been wound upon a curler, and in such cases the damp cloth may be omitted if desired.

In Fig. 7 a plate 22 is shown attached by spring clips 23 to the shell 1. This plate 23 may consist of a thin sheet of aluminum having curved edges, the plate being secured in position without removing the plates 13. This form of heating plate is suitable for grasping wide folds of hair.

The handle members 3 and 4 are pivoted at 24 at a sufficient distance from the shells 1 and 2 to permit such plates as are shown at 22 to project on all sides of the shells as far as is necessary for the largest masses of hair treated at a single operation.

It will be observed that the device described is intended to be held within the hand of the operator, and that its structure renders it particularly suitable for non-professional use as distinguished from previous devices which are suitable for use only by an operator other than the person whose hair is being treated. It is obvious that by means of this device the hair may be subjected either to moist or dry heat and it is also obvious that by suitable modification of the configuration of the plates 13 the device may be adapted to any type of curler though it is also obvious that by the use of plates having an undulating surface such as shown in Fig. 4, the use of such a curler as shown in Fig. 5 may be dispensed with. While in the preferred embodiment of my invention, the heating members 1 and 2 have been described as hollow shells containing electric heating elements, it will be obvious that when electric current is not available, the device may be made with the members 1 and 2 of solid metal as shown in Fig. 9 which can be heated over a lamp, a gas jet, an alcohol burner or by any other source of heat, the removable plates and attachments evidently having the same form and function as when the electric heating elements are used.

A device of the character herein shown and described can be used upon short hair as well as upon long hair, though when the hair is short it will be more convenient to coil the hair on insulated wire from the ends of the hair toward the head and then to grasp the coils with the portion of the tool

opposite the handles. The use of curlers worn over night is avoided by the apparatus herein described, and as before stated, it is primarily designed for use in the home because of its convenience for use upon the head of the operator.

It is very evident that many modifications may be made in the structure of my device without sacrificing any of its advantages or departing from its principle of operation. It is therefore intended that the invention shall be claimed broadly within the legitimate and valid scope of the appended claims.

I claim:—

1. A heater comprising two sections having handle portions crossing each other and pivotally secured together, a heating element mounted within each section, and a heating plate detachably secured upon each of the opposing surfaces of said sections. 70

2. A heater comprising a pair of hollow shell sections each having an insulating lining and a heat conducting cover plate, a pair of plates detachably mounted upon the hollow shells adjacent to said cover plates, 80 and resilient means normally operative to hold said plates apart from each other.

3. A heater comprising a pair of plates having complementary surfaces adapted to receive a fold of hair therebetween, said plates being separated from each other at all points whereby vapor may freely escape from between the plates. 85

4. A heater comprising a pair of handle members pivotally secured to each other in crossed relation, a pair of hollow shells upon the portion of the handle member beyond said pivot, each of said hollow shells containing a heating element, the plates having curved opposing faces detachably secured upon the confronting surfaces of said hollow shells, and means for supplying a current to each of said heating elements. 90

5. A heater comprising two sections having handle portions crossing each other and pivotally secured together, and a heating plate detachably secured upon each of the opposing surfaces of said sections. 100

In testimony whereof I affix my signature in presence of two witnesses.

ALICE M. WRIGHT.
